PACKING COMPANY, OF OMAHA, NEBRASKA, A CORPORATION OF NEBRASKA.

METALLIC ROD-PACKING.

1,370,679.

Specification of Letters Patent.

Patented Mar. 8, 1921.

Application filed November 5, 1917. Serial No. 200,458.

To all whom it may concern:

Be it known that I, JOHN BADEKER, a citizen of the United States, and a resident of Omaha, in the county of Douglas and 5 State of Nebraska, have invented certain new and useful Improvements in Metallic Rod-Packings, of which the following is a specification.

My invention relates to metallic rod-packing for use on the piston-rods and valve-rods of reciprocating steam engines, pumps, air and gas compressors and the like, wherein it is necessary to maintain a fluid-tight joint around a cylindrical reciprocating rod. 10 It is the object of my invention to provide a simple, durable and efficient packing for the purpose set forth, having a packing-ring consisting of a plurality of slidably contacting pieces so formed as to be capable of 15 closure upon the rod to compensate wear of the contacting surfaces, the parts or segments of the packing-ring being of such form that no bending or deformation thereof is required by the closure upon the rod, 20 and being so interlocked that the several parts or segments are constantly maintained in symmetrically-spaced arrangement about the rod. A further object of my invention is to provide in a packing of this class an 25 improved follower device disposed entirely within the packing gland and being carried and guided by the gland instead of being carried upon the rod.

In the accompanying drawings Figure 1 30 is a longitudinal or axial section of a rod-packing embodying my invention, Fig. 2 is a partial front view and partially a transverse section of the same on the plane of the line 2-2 of Fig. 1, Fig. 3 is a front view of 35 the packing-ring alone. Fig. 4 is an axial section of a slightly modified form of the packing-ring, Fig. 5 is a rear side view of one of the inner segments of said packing-ring, Fig. 6 is a front view of said packing-ring with one of the inner segments removed, Fig. 7 is a similar view of a further 40 modification of the packing-ring, Fig. 8 is a rear view of one of the inner segments of the latter ring, Fig. 9 is an axial section of 45 said ring, and Fig. 10 is a detail axial section showing a slightly modified arrangement of the follower and follower-springs. 50

In the illustrated structure, the rod 11 has

the usual enlargement or reinforcement 12 at the end thereof which is connected with 55 the crosshead of the engine, pump or the like. The rod-opening 13 in the cylinder-head 14 is of such size that the enlarged part 12 of the rod may be passed through the same. The stuffing-box 15, usually found 60 in engines and the like, is not directly employed in the structure shown, and the open end of said stuffing-box is partially closed by a back-ring 16 having an outer flange 17 which is clamped between the cylinder-head 65 14 and the rear end of a gland 18. The gland is secured to the head by means of stud-bolts 19 and nuts 20, the gland inclosing peripherally a cylindrical packing-chamber 21 surrounding the rod. The openings 22 and 23 through the front portion 70 of the gland and through the back-ring 16 are of the same diameter as the rod-opening 13 of the cylinder-head, enabling said parts to be passed over the rod-enlargement 12, 75 and also providing a clearance-space around the rod to permit lateral movement thereof resulting from wear of the cross-head, piston and cylinder.

Within the gland at the front end of the 80 packing-chamber 21 there is disposed a split stop-ring comprising two parts 24-24', having plane-surfaced abutting end-portions extending in a plane intersecting longitudinally the axis of the rod, said end- 85 faces of the split ring forming fluid-tight joints with each other, and the front side of the ring forming a fluid-tight joint with the inner face 25 of the gland. The stop-ring is grooved peripherally to receive annular coil springs 26 by which the two parts of the ring are held together. At the rear end of the packing-chamber 21, adjacent to the back-ring 16, there is arranged a follower-ring 27 which fits slidably within the 90 chamber, bearing against the peripheral wall thereof. The bore of the follower-ring is of such diameter that the same may be passed over the rod-enlargement 12 when 95 assembling the parts. In the rear side of 100 the follower-ring there are a plurality of cylindrical pockets, equally spaced circumferentially of the ring, said pockets containing coil springs 28 of which the rear ends bear against the back-ring so as to 105 push the follower forwardly therefrom.

The spring-pockets are preferably formed in lugs 29, as shown in Fig. 2, the material between said lugs at the inner and rearward sides of the ring being removed to reduce 5 the weight of the ring.

- The packing-ring is disposed in the chamber 21 between the follower-ring and stop-ring, and forms a fluid-tight joint with the rod and the rear side of the stop-ring, being 10 pressed yieldingly against the stop-ring by the follower springs and follower. The packing-ring comprises a plurality of main segments 30 of similar form, disposed annularly about the rod and having radial clearance-spaces between the adjacent ends thereof, and a like number of inner segments 31. The outer or peripheral portions of the main segments are grooved to receive annular coil springs 32 by which the segments are 15 pressed yieldingly inward. The front and rear sides of the main segments fit, respectively, against the stop-ring and follower, and at the ends of the main segments the same have plane-surfaced recesses, adjoining 20 the rod and the stop-ring, in which the inner segments fit so as to extend circumferentially across the clearance-spaces between the ends of the main segments, each inner segment being symmetrical to one of 25 said clearance-spaces. Suitable clearance-spaces are provided at the ends of the inner segments, to enable the closing of the packing-ring upon the rod as the inner concave surfaces of the segments are worn away. 30 On the rear sides of the inner segments, adjoining the outer edges thereof, the same have integral rectilinear tongues 33 which fit slidably in corresponding grooves 34 in the main segments. In that form of the packing-ring shown in Figs. 1 and 3, the tongues 33 are coextensive with the outer edges of 35 the segments, and it is necessary that the tongues fit into the grooves so as to form fluid-tight joints therewith. 40 In the modified form of the packing-ring shown in Figs. 4, 5, and 6, the end-portions of the inner segments 310 extend beyond the ends of the tongues 330, and the grooves 340 of the main segments 300 similarly terminate without extending to the ends of the 45 main recesses. With this form of the packing-ring no leakage can occur even though the tongues do not fit the grooves perfectly, since a fluid entering the grooves from the 50 clearance-spaces at the ends of the main segments will be stopped at the joint formed between the flat abutting surfaces near the ends of the inner segments, beyond the ends 55 of the tongues 330. 60 In the further modified form of the packing-ring shown in Figs. 7, 8 and 9, the tongues 331 are provided only near the ends of the inner segments 311, and the grooves 341 are not extended to the clearance-spaces 65 at the ends of the main segments 301. With

this form of the packing-ring, also, no leakage can occur by imperfect fitting of the tongues into the grooves, since the fluid from the clearance-spaces at the ends of the main segments is prevented from entering the 70 grooves by the joints formed between the flat abutting surfaces of the segments adjoining said ends of the main segments.

In each of the described forms of the packing-ring, the tongues and grooves which 75 interconnect the two sets of segments serve the same purpose, namely; that they prevent shifting of the segments relatively to each other about the rod. Obviously such circumferential movement of the segments 80 relatively to each other would change the angular relations of the outer sides of the inner segments to the outer sides of the recesses therefor in the main segments, leaving wedge-shaped spaces between said surfaces through which leakage might occur, and also resulting in narrowing the clearance-spaces between the ends of the segments at one side of the ring, with corresponding 85 widening of the clearance-spaces at the other 90 side of the ring. As the tongues and grooves prevent change of the angular relations of the segments to each other, they also prevent the resulting non-uniformity of the clearance-spaces. It will be seen that when 95 the inner segments are in their normal assembled positions, the outer flat surfaces thereof are related to each other as the sides of an equilateral polygon concentric with the axis of the rod, and that such relation 100 is maintained as the packing wears, each of the several segments moving inward directly radial to the rod, without bending or deformation, the contacting surfaces of the inner and main segments sliding upon each other, 105 and all the clearance-spaces at the ends of the segments being uniformly reduced in width. Thus a very large proportion of the material in the packing-ring may be worn 110 away by the rod before the ring will become useless by permitting leakage of fluid through the same, the maximum wear of the packing-ring being attained when the ring is reduced to a size such that the ends of the main segments engage each other, 115 while the ends of the inner segments correspondingly approach the ends of the recesses in the main segments. As no bending or deformation of the segments in any way other than the wearing of their inner surfaces, is required to permit closure of the packing-ring upon the rod, the packing-ring 120 may be made of any desired and suitable material, and the packing may thus be adapted for use with water, steam, ammonia, acids 125 or other fluids, by selection of materials capable of withstanding the action of the fluid for which the packing is to be used. Lateral movement of the rod, relative to the cylinder-head and gland, is accommodated 130

by sliding of the stop-ring against the inner face 25 of the gland, and by sliding of the rear side of the packing-ring upon the front face of the follower. The follower, being 5 carried and guided by the gland, does not rest upon the rod so as to wear or be worn by the same, and is thus capable of use for an indefinite period without replacement.

A slightly modified arrangement of the 10 follower and follower-springs is shown in Fig. 10, in which the springs 280 are disposed in pockets formed in the back-ring 160, the follower 270 being a plain ring, thinner than the ring 27. By this arrangement, the depth of the gland 180 may be 15 slightly less than with the first described structure.

Now, having described my invention, what I claim and desire to secure by Letters Patent is:

1. In a metallic rod-packing, a packing-ring of uniform substantially rectangular section comprising a plurality of main segments arranged annularly and having radial 25 clearance-spaces between the ends thereof, the adjacent ends of each pair of said segments having plane-surfaced recesses therein adjoining the bore and one side of the ring, said recesses each having a side-face 30 extending transversely of the bore, said recesses having outer faces symmetrical to the bore, inner segments each having plane faces fitting slidably upon the side-faces and outer faces of the recesses in adjacent ends 35 of a pair of the main segments, and slidably interengaging rectilinear tongues and grooves in the abutting side-faces of the main and inner segments, said tongues and grooves being parallel to the outer faces of 40 the inner segments and preventing only such relative movement of the main and inner segments as to change the angular relation of the segments to each other in the plane of the ring.

45 2. A structure as set forth in claim 1, in which the tongues and grooves in the abutting side-faces of the segments are discontinuous longitudinally of said side-faces, whereby overlapping portions of said side-faces are unbroken by said tongues and 50 grooves.

3. In a metallic rod-packing, a packing-ring comprising a plurality of main segments arranged annularly and having clearance-spaces between the ends thereof, there 55 being plane-surfaced recesses in the ends of said segments adjoining the bore and one side thereof, inner segments fitting slidably in the adjacent end-recesses of each pair of 60 the main segments and extending circumferentially across the clearance-spaces between said main segments, and rectilinear tongues on said inner segments extending axially therefrom and fitting into grooves

in the main segments, said tongues and 65 grooves extending tangentially to a common circle concentric with the bore of the ring.

4. In a metallic rod-packing, a packing-ring comprising two sets of annularly arranged segments having clearance-spaces at the ends thereof, the segments of each set extending circumferentially across the clearance-spaces of the other set, and one set of the segments inclosing peripherally the ends 70 of the other set, the engaging surfaces of the segments being plane-surfaced and slideable upon each other to reduce the diameter of the ring, and rectilinear slidably interengaging parts between the two sets of segments at contacting surfaces thereof perpendicular to the rod, said parts extending tangentially to a circle concentric with the bore of the ring and being separable by relative movement of the segments longitudinally of the rod, whereby uniform circumferential spacing of the segments is maintained during closure of the ring. 80

5. In a metallic rod-packing, a packing-ring comprising a plurality of inner segments disposed annularly about the rod and equally spaced circumferentially thereof, said segments each having an inner concave side and plane-surfaced outer sides extending angularly to each other and symmetrically to the rod, main segments each having an inner portion fitting upon the rod alongside the end-portions of a pair of the inner segments and portions fitting slidably over the outer sides of said portions of the inner segments, adjacent ends of each pair of the main segments spaced opposite the intermediate portions of the respective inner segments, and rectilinear slidably interengaging means between the inner and outer segments 95 at contacting surfaces thereof perpendicular to the rod, said means extending parallel to the outer sides of the inner segments, and being freely separable by movement of the inner segments longitudinally of 100 the rod away from the main segments. 105

6. In a metallic rod-packing, a packing-ring comprising two annularly arranged series of segments having circumferential clearance-spaces at the ends thereof, the segments of each series stopping longitudinally of the rod the clearance-spaces of the other series, and one series stopping radially of the rod the clearance-spaces of the other series, all the surfaces of the segments contacting with each other being plane-surfaced and symmetrical to the rod, and rectilinear tongue-and-groove connecting portions between the segments of each series and the adjoining segments of the other series, said connecting portions extending tangentially to a common circle and adapted to prevent 115 non-uniform movement of the several segments. 120 125

ments radially of the rod, and said connecting portions being freely separable by relative displacement longitudinally of the rod.

- 5 7. In a metallic rod-packing, a packing-ring of uniform substantially rectangular section, comprising a plurality of main segments arranged annularly and having radial clearance-spaces between the ends thereof,
- 10 the adjacent ends of each pair of said segments having plane-surfaced recesses therein adjoining the bore and one side of the ring, said recesses each having a side-face extending perpendicularly of the bore, said
- 15 recesses having outer faces symmetrical to the bore, inner segments each having plane faces fitting slidably upon the side-faces and outer faces of the recesses in adjacent ends

of a pair of the main segments, whereby to extend across the clearance-spaces between 20 said main segments and to stop said clearance-spaces axially of the bore, the abutting side-faces of the inner and main segments being provided adjacent to the ends of the main segments with slidably interengaging 25 tongues and grooves which extend parallel with the outer faces of the inner segments and prevent change in the angular relation of the segments to each other in the plane of the ring, the abutting side-faces adjacent to the ends of the inner segments being unbroken by said tongues and grooves, whereby to form a fluid-tight joint between the circumferentially overlapped portions of the segments.

JOHN BADEKER.
